G. J. BARRETT.
ITEM COUNTER FOR CALCULATING MACHINES.
APPLICATION FILED OCT. 14, 1912.

Patented Aug. 25, 1914.

3 SHEETS-SHEET 3.

UNITED STATES PATENT OFFICE.

GLENN J. BARRETT, OF GRAND RAPIDS, MICHIGAN, ASSIGNOR TO BARRETT ADDING MACHINE COMPANY, OF PHILADELPHIA, PENNSYLVANIA, A CORPORATION OF DELAWARE.

ITEM-COUNTER FOR CALCULATING-MACHINES.

1,108,119.

Specification of Letters Patent. Patented Aug. 25, 1914.

Application filed October 14, 1912. Serial No. 725,592.

To all whom it may concern:

Be it known that I, GLENN J. BARRETT, a citizen of the United States, residing at Grand Rapids, Michigan, have invented certain new and useful Improvements in Item-Counters for Calculating-Machines, of which the following is a specification.

My invention relates to improvements in item counters for calculating machines, and an object is to provide an item counter on any standard style of calculating machine by setting aside, as desired, certain recording dials and their actuating means for the purpose.

A further object is to provide means whereby a counter section may be thrown in or out of operative engagement without disturbing the reading on said dials.

Further objects, and objects pertaining to details and economies of construction and operation will definitely appear from the detailed description to follow.

I accomplish the objects of my invention by the devices and means described in the following specification.

The invention is clearly defined and pointed out in the claims.

A structure constituting a preferred embodiment of my invention is clearly illustrated in the accompanying drawing, forming a part of this specification, in which:

Figure I is a plan view of an adding machine, showing a portion broken away to expose my device. Fig. II is a detail left side elevation view of operating mechanism of an adding machine. Fig. III is a sectional elevation view of an adding machine showing my improvement applied, taken on line 3—3 of Fig. I. Fig. IV is an enlarged detail sectional view of the transfer part of an adding machine with my improvement, taken on line 4—4 of Fig. V. Fig. V is a detail sectional view taken on line 5—5 of Fig. IV. Fig. VI is a detail rear view of the tripping and stopping member of the transfer mechanism. Fig. VII is an enlarged detail fragmentary perspective view of my item counter lever and coöperating parts, with the relation of certain parts shown by dotted lines. Fig. VIII is an enlarged detail front sectional view of main parts shown in Fig. VII taken on line 8—8 of Fig. III.

Similar numerals of reference refer to similar parts throughout the several views,

and the sectional views are taken looking in the direction of the little arrows at the ends of the section lines.

Considering the numbered parts, I have shown my device adapted to an adding machine of the type covered by my Patent No. 976,336 of Nov. 22, 1910. This is a key set, handle operated machine. In such a machine, dial actuating reciprocating members advance a predetermined space and are forced back to normal position during the operation of a crank or handle. The transfer of the tens is effected in a machine of this type by storing power against the tension of a spring, and providing means whereby when a dial of one denomination passes the carrying point, the dial next higher is driven by virtue of the power stored as aforesaid, an extra unit, thus recording the ten advanced from the lower dial.

In a mechanism of this sort, each dial tends to rotate at each stroke of the handle one space more than the number of spaces indicated by the depressed finger key corresponding to said dial. This is normally prevented by means of a stop which limits the rotation of the dial to the number of spaces represented by the coöperating depressed finger key. When the transfer point is reached on any dial the rotation of this dial trips the stop coöperating with the dial of the next higher denomination and allows said dial to rotate one extra space. All of this mechanism is illustrated and described in my Patent No. 976,336, dated November 22, 1910. My present invention comprises mechanism whereby this stop is thrown out of the way so that at each movement of the handle the dial coöperating with said stop will advance one space. It is not altogether new to provide mechanism whereby the normal stop for any denomination is permanently thrown out of the way, when at every movement of the handle its coöperating dial will register "1". This counts the handle strokes on this particular dial.

It is an object of my invention to overcome a difficulty in such a structure. If the counter be made operative when the machine is normal, one extra "1" will be registered on the counting dial by reason of throwing out the normal stop.

The object of my present device is to merely position certain parts by suitable

switching means so that this stop is removed only as the handle is actually operated, and thus the item counter may be thrown in and out of operative engagement without disturbing the reading of the counter dials.

In Fig. VI appears the carrying parts. In Fig. IV a trigger 1 is just about to contact with the pin 2 on the swinging member 3. See Fig. VI. Extending from this movable member is an ear 5 which is the normal stop for the dial actuating reciprocating member 4 of the next higher denomination.

3', see Figs. IV and VII, is an upwardly projecting portion of the member 3, against which my device contacts during the operation of the handle.

Fig. I shows a plan view of a calculating machine made according to my Patent No. 976,336, of Nov. 22, 1910, with my device added. 6 is the main operating shaft and 7 the operating handle. 8 is a sector on the left side of machine shown in Fig. II. 14 is a locking pitman having a reciprocating movement during the operation of the machine, as more fully described in my above mentioned patent.

My invention may be applied to any member having a reciprocating movement in synchrony with the handle, but I find it convenient in this instance, to coöperate with the part 14. The connections back to the shaft 6 may be traced through the connecting parts 13, 12, 11, 10, 9 and 8, all of which are fully described in my said patent.

35 The keys and their connections and stops and the actuating handle, and the various means making up such a machine are here illustrated, but not particularly described. The description is complete in my said
40 former patent.

15 is a lever with an arm extending through a slot 14' in the link 14. During every movement of the handle 7, link 14 moves toward the rear of the machine and the forward portion of its slot 14' contacts with the lever 15, causing the latter to swing on the vertical pivot 16 against the tension of the spring 17 provided to hold the same in normal position. A support 21 is provided for the lever 15 and pivot or fulcrum 16 and is secured to the side of the case. At the other extremity of the lever 15 is the sliding member 18 adapted to slide under the shouldered rivet 20. One end of this slide 18 is bifurcated to guide it and keep its position on the lever 15. Extending from slide 18 is an ear 25 which is adapted to be received by the bifurcated end of 19 18' is a portion of 18 which is adapted to strike 37 when in operative position at each movement of the handle; hence movement of the link 14. Extending through the keyboard of the machine is the item counter switch finger piece 22 and connecting parts to the switch 19.

23 is the pivotal point through the key plate of the machine.

22 is rigid with 19, and when 22 is moved to right or left 19 has a corresponding movement.

When the finger piece 22 is normal, as shown in Fig. 1, 18' misses 3' during each handle movement. When the finger piece 22 is moved to the left, then 18' falls behind 3', and when 14 strikes 15, 3' is forced toward the front of the machine, thus giving its coöperating dial a transfer movement of one space. Thus it will be readily understood that a movement of 18 back and forth, actuated by 22 as described, will in no way affect 3' assuming that the operating handle is in normal position, and that it is the movement of this handle which trips the transfer stop. 75 80

This item counter switch and finger piece 85 may be placed anywhere on the keyboard, but I have chosen to place it between the second and third column from the left, thus making the last two dials counters, which record every handle stroke. 90

Having thus described my invention, what I claim as new and desire to secure by Letters Patent is:

1. In a calculating machine having handle operating mechanism, dial mechanism with transfer devices, the combination of movable transfer stops; dial actuating reciprocating members normally arrested by said stops, a lever pivotally mounted adjacent to one of said movable transfer stops; contact connection between said lever and said handle operating mechanism; a spring for returning said lever to normal position; a sliding, tripping member carried by one end of said lever adapted to slide in and out of contact relation with said movable transfer stop; a switching member adapted to contact with said sliding tripping member; a finger piece on the keyboard of said adding machine and suitable connections between said finger piece and said switching member, substantially as described. 110

2. In a calculating machine having a keyboard board and handle operating mechanism, and dial mechanism with transfer devices, the combination of movable transfer stops; dial actuating reciprocating members normally arrested by said stops; a lever pivotally mounted in said calculating machine; connections between said lever and said handle operating mechanism; a movable tripping member carried by one extremity of said lever, and adapted to move in and out of operative relation to said movable transfer stop; a switching member connected to said movable tripping member; a finger piece on the keyboard of said adding machine and suitable connections between said finger piece and said switching member, substantially as described. 115 120 125 130 135

3. In a calculating machine having a keyboard and handle operating mechanism, the combination of movable transfer stops; dial actuating reciprocating members normally arrested by said stops; a lever pivotally mounted in said calculating machine; connections between said lever and said handle operating mechanism; a movable tripping member carried by said lever normally out of operative position with reference to said movable transfer stops; and means connected to the keyboard of said calculating machine for throwing said tripping member into operative position with reference to one of said movable stops, substantially as described.
4. In a calculating machine having handle operating means and dial mechanism with transfer means, the combination of movable transfer stops; dial actuating reciprocating members normally arrested by said stops; a movable member normally out of engaging relation with said transfer stops; actuating connection between said movable member and said handle operating means; and means connected to the keyboard of said calculating machine for throwing said movable member into engaging relation with one of said transfer stops, substantially as described.
5. In a calculating machine having handle operating means and dial mechanism with movable transfer stops; a reciprocating member actuated by said handle operating means; tripping means carried by said reciprocating member adapted to be moved into and out of engaging relation with one of said transfer stops; and a suitable fin-

ger piece for moving said tripping means, substantially as described.

6. In a calculating machine, having handle operating means and a dial means with movable transfer stops; a reciprocating member actuated by said handle operating means, and adapted to be thrown into and out of engaging relation with one of said transfer stops, substantially as described.

7. In a calculating machine having a handle operating means and a dial means with movable transfer stop; means connected to said handle operating means for moving one of said movable transfer stops; and means for rendering said moving means inoperative, substantially as described.

8. In a calculating machine having a handle operating means and a dial means with movable transfer stops, shiftable means actuated by said handle for moving one of said stops at will to register the impulses of said handle.

9. In a calculating machine having a handle operating means and a dial means comprising transfer mechanism, shiftable means actuated by said handle and disposed to be moved into or out of engagement with the transfer mechanism of the higher denomination of the dials whereby a portion of the dials may be used as an item counter.

In witness whereof, I have hereunto set my hand seal in the presence of two witnesses:
